UNITED STATES PATENT OFFICE.

CHARLES F. PAIGE, OF DENVER, COLORADO.

REFRIGERATOR.

SPECIFICATION forming part of Letters Patent No. 470,167, dated March 1, 1892.

Application filed May 19, 1891. Serial No. 393,343. (No model.)

To all whom it may concern:

Be it known that I, CHARLES F. PAIGE, a citizen of the United States of America, residing at Denver, in the county of Arapahoe and State 5 of Colorado, have invented certain new and useful Improvements in Refrigerators; and I do declare the following to be a full, clear, and exact description of the invention, such as will enable others skilled in the art to which it ap-

10 pertains to make and use the same, reference being had to the accompanying drawings, and to the figures of reference marked thereon, which form a part of this specification.

My invention relates to improvements in 15 refrigerators; and its main object is to prevent the accumulation of ice or frost upon the pipes through which the cooling-liquid is forced. These pipes being cooled below the 20 freezing-point, the surrounding moisture naturally collects thereon in a congealed or solidified form. As this incrustation thickens, a "blanket," so to speak, is formed around the pipes, rendering them practically useless for refrigerating purposes.

25 In my improved construction the uppermost pipe is perforated and contains salt-water or other suitable liquid under pressure. The pipes below the perforated pipe are so arranged and supported in connection with 30 drip-brackets that as the liquid passes from the perforated pipe it drips over the whole series of pipes in succession and finally passes into a trough at the bottom of the series, whence it is conducted to any suitable recep- 35 tacle.

My improved construction will be fully understood by reference to the accompanying drawings, wherein is illustrated an embodiment of my invention.

40 In the drawings, Figure 1 is a vertical section taken through the upper portion of the refrigerator. Fig. 2 is a similar view of a modified form of construction. Fig. 3 is a fragmentary view, taken on an enlarged scale, 45 of the mechanism shown in Fig. 1. Fig. 4 is a longitudinal section taken on the line xx , Fig. 1, the pipes being shown in elevation.

In the views, wherein similar reference characters designate corresponding parts of 50 the mechanism, let the numeral 10 designate the outer walls of the refrigerator, which are constructed in the usual way. Within these

walls and in the upper portion of the chamber are located the interior walls 15 15, forming a double-inclined flue or air-conduit 20, 55 the inner wall of which forms an apex at the top. The conduit 20 opens at both extremities into the chamber 25 below, thus giving a free circulation for the air from chamber 25 through the flue 20 and back again to the 60 chamber.

In order to increase the cooling-surface over which the air passes, it is preferable to arrange the cooling-pipes 30 on an inclined plane formed by one side of the inner wall 15, 65 to which are secured brackets 35, composed of a suitable seat 40, upon which the pipe 30 rests, and an inclined drip-plate 45 above this seat and terminating, preferably, directly above the center of the pipe, the seat and the 70 drip-plate being connected by the web 50 of the bracket, through which portion the bracket is bolted or otherwise suitably secured to the wall 15, as shown.

The perforated pipe 55 is located and suitably secured above the inclined series of cooling-pipes. Above this perforated pipe and almost in contact therewith is a plate 60, having downwardly-inclined sides adapted to throw the liquid issuing from the pipe back 80 on itself and thence to the first pipe 30 of the inclined series below, whence it is guided by the first drip-plate to the next pipe of the series, and so on to the last, whence it passes to a trough 65. 85

Another arrangement of pipes and drip-plates is shown in Fig. 2. In this figure the cooling-pipes 30 are arranged in two vertical series on opposite sides of a central vertical air-flue 70, connected with flues 75, leading 90 from the main chamber 25. The pipes 30 in this modified form are supported by brackets 80, secured to the walls of the air-flue. On the opposite side of the flue from each pipe 30 and somewhat higher than the pipe is secured a downwardly-inclined drip-plate 85, provided with a suitable supporting-brace. The perforated pipe 55 is supported above the vertical air-flue 70, so that the liquid escaping therefrom shall fall on the first drip-plate 100 85, whence it is conducted to the pipe 30 on the opposite wall of the air-flue, and from this pipe to the next drip-plate below, and so on until the lowest pipe is reached, when this

liquid is conducted into a trough 90. It will thus be observed that by this simple construction salt-water or other suitable liquid may be dripped over the pipes continually, whereby the usual incrustation resulting from congealed moisture is obviated, while the increased cooling-surface afforded by the drip-plates is an important feature.

It may be well to state that all parts of the mechanism exposed to moisture or liquid should be constructed of some non-corrodible metal, as galvanized iron.

Having thus described my invention, what I claim is—

15 1. In a refrigerator, the combination of a series of cooling-pipes arranged in the upper portion thereof, of a perforated non-congealable liquid-containing drip-pipe located above the cooling-pipes, and downwardly-inclined 20 drip-plates secured to the walls supporting

the pipes and so arranged with reference to the pipes that the liquid from the drip-pipe is conducted successively to the cooling-pipes of the series, substantially as and for the purpose set forth.

2. In a refrigerator, the combination, with the cooling-pipes, of brackets, each consisting of a seat and a downwardly-inclined drip-plate above said seat, and a non-congealable liquid-supply source located above the brackets, the brackets being so arranged that the liquid falling from said source is conducted to the cooling-pipes successively, substantially as and for the purpose set forth.

In testimony whereof I affix my signature in presence of two witnesses.

CHARLES F. PAIGE.
